US00D857497S

(12) **United States Design Patent** (10) Patent No.: **US D857,497 S**
(45) Date of Patent: **** Aug. 27, 2019**

(54) **PUSH BUTTON CLOSURE**

- (71) Applicant: **Stolle Machinery Company, LLC**,
Centennial, CO (US)
- (72) Inventors: **Dennis C. Stammen**, Brookville, OH
(US); **Patrick K. McCarty**, Dayton,
OH (US)
- (73) Assignee: **Stolle Machinery Company, LLC**,
Centennial, CO (US)
- (**) Term: **15 Years**
- (21) Appl. No.: **29/673,984**
- (22) Filed: **Dec. 19, 2018**

CLAIM

The ornamental design for a push button closure, as shown and described.

DESCRIPTION

FIG. 1 is a top perspective view of the push button closure; FIG. 2 is another top perspective view of the push button closure;

FIG. 3 is a bottom perspective view of the push button closure;

FIG. 4 is another bottom perspective view of the push button closure;

FIG. 5 is a top plan view of the push button closure;

FIG. 6 is a bottom plan view of the push button closure;

FIG. 7 is a side elevational view of the push button closure; and,

FIG. 8 is a section view of the push button closure taken in the direction of line 8-8 shown in FIG. 5.

The broken lines shown represent unclaimed subject matter and form no part of the claimed design.

1 Claim, 7 Drawing Sheets
